FAN

Edward L. Anderson, Detroit, Mich., assignor to
 American Blower Corporation, Detroit, Mich.,
 a corporation of Delaware

Application June 24, 1936, Serial No. 87,032

18 Claims. (CL 230—233)

My invention relates to air handling apparatus and in particular to a means and method of sound absorption of air handling fans, casings and ducts associated therewith.

5 It is my object to provide in a unit adapted to heating, cooling and humidification, a fan having a sound absorbing outlet.

It is my object to provide a form of outlet which reduces the sound from the apparatus, 10 particularly when used in connection with metal casings. It is understood that such fans used in units and other similar installations in connection with enclosures such as homes, theatres, schools and churches must be as nearly noiseless as possible.

15 It is the object of my invention to provide a fan having a high speed and relatively high velocity outlet of air that will be noiseless, while at the same time permitting the fan to travel 20 at its most efficient speed.

Referring to the drawings:

Figure 1 is a top plan view of a unit embodying my invention with the metal enclosing casing in section, a portion of the radiator in section, 25 and a portion of the fan outlet chamber in section. The section of Figure 1 is taken on the line 1—1 of Figure 3.

Figure 2 is a section on the line 2—2 of Figure 1.

30 Figure 3 is a section on the line 3—3 looking in the direction of the arrows of Figure 1.

Referring to the drawings in detail, I designates the bottom of a metal casing which has the top 2 and sides 3 and 4. An end 5 is provided 35 with an air inlet 6 in which is located a filter 7. The air passes through the filter and then through the humidifying chamber 8 having a humidifying spray nozzle 9 and baffle plate 10. The air then passes through the radiator 11, which may either be for cooling or heating purposes, and thence into the fan chamber 12. The bottom of this chamber is inclined at 13 so that any entrained moisture may drain away 40 through the pipe 14.

45 Within the air inlet chamber 12 is mounted the fan casing 15 in which is located a fan 16 mounted on the shaft 17 that carries a pulley 18 which is driven by a belt 19 from a smaller pulley 20 on the armature 21 of an electric 50 motor 22. The lateral dimensions of this vortex fan casing 15 are small in comparison with the lateral dimensions of the chamber 12. The cover of the chamber 12 is inclined as at 23.

The sides of the fan casing 15 are provided 55 with air inlet openings 24 through which the

air enters and is then delivered by the fan 16 from the casing 15 tangentially through the outlet opening 25 into the outlet passageway 26.

This passageway is lined with a sound deadening material 27. The passageway expands vertically and laterally as indicated by the positioning of the upper wall 28 and lower wall 29, which progressively are further apart as the air progresses away from the fan 16. The angular wall 30 acts as a baffle wall for directing the 10 air into the passageway 26.

The side walls of the passageway 31 and 32 likewise are progressively further apart towards the air outlet 33. These side walls are likewise 15 insulated with the sound deadening material 27.

The course of the air is first through the filter 7 after entering through the passageway 6, thence through the humidifying chamber 8, radiator 11, into the relatively large chamber 12, whence the air enters through the air inlet opening 24 into the eye of the fan and is discharged from the casing 15 through the opening 25 into the sound insulated, vertically and laterally expanding passageway 26, whence it leaves through the opening 33.

Despite the fact that this fan is operating within a thin sheet metal casing which emphasizes any noise and handles a large volume of air with an air discharge at a substantial velocity, nevertheless the operation of the unit is 30 substantially noiseless. This is due to the arrangement of the parts, particularly the air outlet.

The insulation 27 which is parallel to the rear wall 30 is held in position as it rests upon the 35 flange 30a at its bottom and against the adjacent edge at its top of the top lining 21a. The forward end of the top lining 21a engages with the wall 28a, which forms a recess for receiving the lining 21a. The lower covering of insulation 40 on the wall 29, which insulation is designated 29a, is likewise inserted behind the shoulder 29b at its forward end and is overlapped and engaged at its rear end by the lip 15a of the fan casing 15 which is suspended from the top 23 of 45 the air inlet chamber 12.

It will be understood that I desire to comprehend within my invention such modifications as may be necessary to adapt it to varying conditions and uses.

Having thus fully described my invention, what I claim as new and desire to secure by Letters Patent, is:

1. In combination, a fan and surrounding fan casing, and an extended air outlet separate from

said fan casing and having a sound deadening lining material therein and disposed in part between portions of said air outlet and said fan casing and providing support for a part of said fan casing on said air outlet.

2. In combination, a fan and fan casing, and an extended air outlet with progressively expanding side, top and bottom walls and having a sound deadening lining material therein, said outlet being arranged at an acute angle to the line of discharge of the air from the fan casing, and having an angular positioned baffle wall for directing air into said extended outlet.

3. In combination, a fan casing, a fan there-
15 in adapted to discharge upwardly through the top side of said casing, and an air outlet passage-
way disposed at an acute angle to the direction
of fan discharge and communicating with said
casing comprising top, bottom and side walls pro-
20 gressively expanding from the inlet to the outlet
passageway to the outlet thereof and provided
with an interior sound absorbent lining, said out-
let passageway wall comprising a sound insulated
25 annular section positioned adjacent said fan for
directing the air discharged therefrom into said
expanded outlet passageway.

4. In combination, an air inlet chamber a fan
casing located therein and communicating there-
with, a fan in said fan casing, a substantially
30 horizontal discharge passageway communicating
with said fan casing and disposed at an acute
angle to the discharge of said fan, said discharge
passageway being progressively larger from its
35 inner end towards its outer end comprising a ver-
tically and laterally expanding opening and hav-
ing therein a lining of sound-deadening material.

5. In combination, an air inlet chamber, a fan
casing suspended therein from the top thereof,
said fan casing having an outlet opening com-
40 municating with an outlet opening in the top of
said chamber and said fan casing having an air
inlet opening communicating with said cham-
ber, a discharge passageway provided with an in-
45 terior sound absorbent lining and extending from
said air outlet opening of the fan casing pro-
gressively larger laterally from the inlet end of
the outlet passageway to the outlet end thereof,
and a fan in said fan casing, a portion of said fan
50 casing being supported by said discharge passag-
eway and being insulated therefrom by a portion
of said lining.

6. In combination, an air inlet chamber, a fan
casing suspended therein from the top thereof,
55 said fan casing having an outlet opening com-
municating with an outlet opening in the top of
said chamber and said fan casing having an air
inlet opening communicating with said cham-
ber, a discharge passageway provided with a lining
60 of sound absorbent material and extending
from said air outlet opening of the fan casing pro-
gressively larger laterally from the inlet end
of the outlet passageway to the outlet end thereof,
and a fan in said fan casing, said outlet pas-
65 sageway being disposed substantially parallel to
the line of flow of the air entering the first-men-
tioned air chamber and having the lining thereof
supporting the forward edge portion of said fan
casing.

7. In combination, an air inlet chamber, a fan
70 casing suspended therein from the top thereof,
said fan casing having an outlet opening com-
municating with an outlet opening in the top of
said chamber and said fan casing having an air
inlet opening communicating with said inlet
75 chamber, a discharge passageway extending from

said air outlet opening of the fan casing progres-
sively larger laterally from the inlet end of the
outlet passageway to the outlet end thereof, and a
fan in said fan casing, said outlet passageway
having a sound absorbent lining therein and be-
ing disposed substantially parallel to the line of
flow of the air entering the first mentioned air
chamber and at an angle to the line of discharge
of the air by the fan from the fan casing and
said fan casing having one edge supported by said
outlet passageway and insulated therefrom by a
portion of the lining thereof.

8. A new article of manufacture for use as a
fan discharge passageway comprising a casing
adapted to be horizontally disposed and having
15 laterally diverging flat side walls and diverging
flat top and bottom walls, with an air inlet open-
ing in the bottom wall and a fixed wall portion
diagonally disposed across the end of the casing
over the air inlet opening thereto for directing
20 the air into said fan discharge passageway.

9. A new article of manufacture for use as an
air outlet passageway comprising a substantially
horizontal passageway having diverging side walls
and diverging top and bottom walls, said diver-
gence taking place from the inlet to the outlet
25 end of the passageway, said passageway having
an air inlet opening on the bottom of the inlet
end, a fixed wall portion diagonally disposed
across the inlet end over the air inlet opening,
30 and having an air outlet opening at the outlet
end.

10. In combination, an air inlet chamber hav-
ing an air inlet opening at one end, said chamber
decreasing in size from the air inlet opening to
wards the air outlet opening and having an air
outlet opening therein, a fan casing communicat-
35 ing with the air inlet chamber suspended in the
air outlet opening of the air inlet chamber and
communicating therewith, a fan in the fan cas-
ing, and an angularly disposed, expanding dis-
charge casing associated with the fan casing out-
40 let whereby the air discharged therefrom has its
direction of discharge changed and is permitted
to expand before it is discharged from the pas-
45 sageway.

11. A discharge casing for a wheel type blower
having an impeller wheel, a housing including a
spiral outer wall adjacent to the periphery of
the wheel, and a discharge outlet lying in a plane
approximately tangential to the periphery of the
50 wheel, said casing including a side lying in the
plane of said discharge outlet and an opposed
side beginning substantially as a continuation of
the spiral of said outer wall and extending as a
55 plane surface, diverging from the first side at
an acute angle with respect thereto, and two
other sides, the last two sides being divergently
disposed so as to form a rectangular conduit pro-
gressively increasing in cross-sectional area at a
60 greater rate than that of the space between the
periphery of said wheel and said housing, the
length of said discharge casing with respect to
the length of said discharge outlet being such
that substantially all atmospheric vibrations
65 within the sonic range originated by said im-
peller wheel impinge upon a side of the cas-
ing.

12. A discharge casing for a wheel type blower
having an impeller wheel, a housing including a
spiral outer wall adjacent to the periphery of
the wheel, and a discharge outlet lying in a plane
approximately tangential to the periphery of the
70 wheel, said casing including a side lying in the
plane of said discharge outlet, an opposed side
75

beginning substantially as a continuation of the spiral of said outer wall and extending as a plane surface diverging from the first side at an acute angle with respect thereto, and two other sides, the last two sides being divergently disposed so as to form a rectangular conduit progressively increasing in cross-sectional area at a greater rate than that of the space between the periphery of said wheel and said housing, the length of said discharge casing with respect to the length of said discharge outlet being such that substantially all atmospheric vibrations within the sonic range originated by said impeller wheel impinge upon a side of the casing at such angles that the majority of such vibrations may be reflected against another side of the casing.

13. A discharge casing for a wheel type blower having an impeller wheel, a housing including a spiral outer wall adjacent to the periphery of the wheel, and a discharge outlet lying in a plane approximately tangential to the periphery of the wheel, said casing including a side lying in the plane of said discharge outlet, an opposed side beginning substantially as a continuation of the spiral of said outer wall and extending as a plane surface diverging from the first side at an acute angle with respect thereto, two other sides, the last two sides being divergently disposed so as to form a rectangular conduit progressively increasing in cross-sectional area at a greater rate than that of the space between the periphery of said wheel and said housing, the length of said discharge casing with respect to the length of said discharge outlet being such that substantially all atmospheric vibrations within the sonic range originated by said impeller wheel impinge upon a side of the casing, and sound-absorbing material forming at least the inner surfaces of said sides.

14. A discharge casing for a wheel type blower having an impeller wheel, a housing including a spiral outer wall adjacent to the periphery of the wheel, and a discharge outlet lying in a plane approximately tangential to the periphery of the wheel, said casing including a side lying in the plane of said discharge outlet and an opposed side beginning substantially as a continuation of the spiral of said outer wall and extending as a plane surface diverging from the first side at an acute angle with respect thereto, two other

sides, the last two sides being divergently disposed so as to form a rectangular conduit progressively increasing in cross-sectional area at a greater rate than that of the space between the periphery of said wheel and said outer wall, the length of said discharge casing with respect to the length of said discharge outlet being such that substantially all atmospheric vibrations within the sonic range originated by said impeller wheel impinge upon a side of the casing at such angles that the majority of such vibrations may be reflected against another side of the casing, and sound-absorbing material forming at least the inner surface of said sides.

15. In combination, a fan and fan casing, and an extended air outlet with progressively expanding side, top and bottom walls and having a sound deadening lining material therein to form sound deadening walls, said outlet being arranged at an acute angle to the line of discharge of the air from the fan casing, in which all lines of discharge from the fan intersect a sound deadening wall of the discharge passageway.

16. In combination, a fan rotor and fan casing having an extended air outlet with pairs of oppositely spaced progressively expanding sound deadening walls constituting an extended air outlet disposed at an acute angle to the line of discharge of air from the said fan casing and being arranged so that all lines of discharge from the fan intersect a sound deadening wall of the discharge passageway.

17. In combination, a fan rotor and fan casing having an extended air outlet with sound deadening walls progressively expanding in all directions to form a passageway and constituting an extended air outlet disposed at an acute angle to the line of discharge of air from the said fan casing and being arranged so that all lines of discharge from the fan intersect a sound deadening wall in said passageway.

18. In combination, a fan rotor and a fan casing, an extended air outlet in the form of a hollow truncated pyramid having sound deadening walls, said fan and fan casing adapted to discharge therein and being located adjacent the apex end of said pyramid, said fan being so located with respect to the pyramid that all lines of discharge from the fan intercept a sound deadening wall of the pyramid.

EDWARD L. ANDERSON.
